STREET SIGNAL ADAPTER

Mason V. Green, Lansing, Mich., assignor to
Frank D. Hayes, Lansing, Mich., as trustee, for
F. D. Hayes Electric Company

Application April 17, 1939, Serial No. 268,195

4 Claims. (Cl. 177—337)

The object of my device is to provide an electric device that may be used in combination with the ordinary alternating traffic signal device, for converting the old standard signal units into vehicle actuated signals.

A further object is to provide an electric signal adapter that will function the conventional type, or types of alternating traffic signal units, so as to allow continuous traffic along a main street, subject to interruption only on the approach of a vehicle on the intersecting street.

Another object is to provide an adjustable traffic adapter that will automatically repeat, or continue an existing actuated street signal during a predetermined period of the timer signal cycle.

These several objects are attained in the preferred form by the construction and arrangement of the various parts and sections as more specifically hereinafter set forth.

Similar parts on all drawings are marked by similar numerals or letters.

Fig. 1 is a front elevation of the adapter device, with the front casing removed, showing the general arrangement of the different operating unit sections.

Fig. 2 is a right side elevation of the assembled adapter, showing the relative position of the various operating units and circuit terminal contact elements.

Fig. 3 is a left side elevation of the adapter, showing the power units and the adjustable circuit contacts.

Fig. 4 is a vertical sectional view taken on the line 4—4 of the Fig. 2, showing the general arrangement of the operating parts within the outer tier of instrument.

Fig. 5 is a vertical sectional view taken on the line 5—5 of the Fig. 2, showing the power unit back gearings.

Fig. 6 is a top view of the assembled adapter shown in Fig. 1, showing the double relay units and the circuit terminals provided thereon.

Fig. 7 is a cross-sectional view taken on the line 7—7 of the Fig. 1, showing the relative position of the various operating parts within the call registering unit.

Fig. 8 is an elevation of a typical alternating street signal timer unit, illustrating one form of geared means commonly used for operating the different signal circuits, alternately for both intersecting streets.

Fig. 9 is a side elevation of the timer unit shown in the Fig. 8, illustrating the different signal cir-

cuit contact terminals, and means for actuating same in a predetermined sequence.

Fig. 10 is an illustrative diagram showing the various phases and operating sequence of the combined signal system.

Fig. 11 is a wiring diagram of the adapter device, and its connected operating units and signal lights.

It is to be understood that I do not claim a complete traffic signal device, but only the adapter unit, to be used with some form of suitable detector, and an alternating electric signal timing unit, for converting same into a vehicle actuated signal for at least one of the intersecting streets.

I have illustrated my device as applied to a continuous signal, if uninterrupted, on a main street, and the vehicle actuated signal on the intersecting street, and as indicated in the Fig. 11 of the drawings.

Each traffic actuation, or electrical impulse to the adapter, from the connected detector G installed beneath the actuated street surface, will be referred to as a "call," or "call period," and the various street signals are indicated as "red," "green," or "amber," now commonly used for all traffic purposes.

I will now describe more fully the detail construction of my device, referring to the drawings and the marks thereon.

In general, the adapter comprises a combination of a call registering unit A, a timing unit B, a time extension interlocking relay C, a transfer relay D, and a call canceling relay E, all electrically connected in various electric circuits leading from the detector, adapter and through the timing unit to the different street signal lights, as shown in the Fig. 11.

The call registering unit A, comprises a sensitive galvanometer relay instrument 1, an induction motor 2, and various connecting operating elements for functioning different contact terminals connected within the electric circuits passing therethrough. The sensitive relay 1 is fixedly mounted on the front frame panel 3, and is provided with a permanent horse-shoe magnet 4 centrally located therein. A rotor 5 is pivotally mounted between the magnet pole ends, and carries an armature winding 6 wound thereon, and which is electrically connected by the circuit wires 7 and 8 to the terminals of a traffic detector G installed across the traffic actuated street, beneath the surface thereof. A switch button circuit may also be connected for pedestrian use. The detector G, herein illustrated

is formed of a permanent magnet bar 9, surrounded by a continuous induction coil winding 10. A movable circuit contact arm 11 is mounted on the rotor 5, rotatable therewith, and is provided with an iron point tip *a*. A fixed terminal 12 formed with a permanent magnet end tip, is mounted within the relay casing, positioned to engage, and retain thereon, the movable contact arm 11, whenever the same is rotated thereto by electrical reaction from the connected detector G. The relay terminals 11 and 12 are connected within an electric circuit leading to the induction motor 2, by the circuit wires 13, 14 and 14a. The small induction motor 2 may be of any suitable standard type, provided with back gears 15, 16 and 17, or similar back gears, and is fixedly mounted on the central frame panel 18, directly opposite the sensitive relay 1. The motor gear 17 is mounted on a stud shaft 19 which is projected outside the motor casing wall, and through the supporting frame panel 18. Fixedly mounted on the outer end of the stud shaft 19 is a reset toggle arm 20. The arm 20 is formed with a V-shaped head cam *b* on the extended end thereof, and positioned symmetrical thereto. A reset arm 21 is pivotally mounted on the back of the frame panel 3, and extended therethrough with its free end projected between the terminal members 11 and 12 of relay 1, for separating same whenever said reset arm is rotated. Hingedly attached to said reset arm 21, is an operating arm 22, mounted with its outer end positioned above the toggle arm cam head *b*, and contacted therewith through the end arm roller 23, designed to roll on the cam face *b* under reaction of the connected spring *c*, as the arm 20 is rotated clockwise by the connected motor 2. When the roller 23 reaches the cam apex it will then slide down the opposite cam face and rotate the reset arm 21 sufficiently to open the terminals 11 and 12, and thus disconnect the motor circuit. Fixedly attached to the side of the toggle arm 20, is a rigid side cam 24, formed and positioned to engage a terminal post 25 mounted on the side of a spring terminal contact 26, and in a manner for depressing same and separating the terminal 26 from its corresponding fixed terminal 27 whenever the side cam 24 is rotated. The toggle arm 20 and cam 24 are returned to their normal position by a connected spring 32, when the motor circuit is broken. Both the terminals 26 and 27 are mounted on an insulating block 28 which is fixedly attached to a gear sector 29, rotatably pivoted over the shaft 19, and is actuated by an adjusting screw 30 and connecting pinion gear 31, providing adjusting means for timing the terminals 26 and 27 in relation to the opening cam 24. Fixed terminals 33 and 34 are mounted on the central frame panel 18 by means of an insulating block 35 fixedly attached thereto. Corresponding movable terminals 33a and 34a are attached to an insulating block 36 which is pivotally mounted therebeneath by the pivot shaft 37 projected from the side of panel 18, and the terminals 34 and 34a are held normally open by the connected spring 38, when otherwise unrestrained. An operating plug 39 is fixedly attached to the side of the pivoted insulating block 36, positioned thereon to engage the toggle arm 20 when same is rotated by the motor 2, for tilting the block 36 and closing the contact terminals 33 and 33a, automatically locking the block and terminals in that position by the attached latch arm 40 and lock arm 41 mounted

thereabove. A call cancelling relay E is fixedly mounted on the central frame panel 18, positioned above the lock arm 41, and is designed to contact and disengage said arm 41 from the latch arm 40, by the extended hammer arm *i* attached to the relay armature plate *d*. Whenever the latch arm 40 is disengaged, the contact terminals 33 and 33a will open and the contact terminals 34 and 34a will automatically close under reaction of the connected spring 38. A pair of circuit contact terminals 42 and 43 are mounted on the movable armature plate *d* of the relay E, insulated therefrom by the insulating block 44, and positioned normally open. A contact plug 44a of insulating material is fixedly attached to the panel 18, positioned thereon to engage and close the terminals 42 and 43 whenever the relay E is energized and the armature plate *d* closed thereon. Suitable multiple electric circuit connecting terminal units 45 and 45a are fixedly attached to one edge of the frame panel 18 for more conveniently connecting the adapter unit with other electric element units with which it is to be operated.

The timing unit B comprises a small reversible induction motor 46 fixedly mounted on the back frame panel 47, the motor being operative with a series of adjustable circuit contact terminals mounted adjacent thereto. The motor 46 may be any suitable type of reversible induction motor provided with back gears *e*, *f*, and *g*, or similar back gears, and is provided with a central stud shaft 48 projected through the inner motor casing wall and supporting frame panel 49. A pinion gear 50 is mounted on the stud shaft 48, positioned inside the panel 49, and engages a toothed timing rack 51 slidably mounted crosswise the panel, operative in both directions. Along one side of the panel 49 is mounted the insulating terminal block 52 fixedly attached to the panel face, and carries mounted thereon three terminal points 53, 54, and 55. Directly beneath the fixed terminal block 52 and opposite one end of the timing rack 51, is a movable insulating block 56 pivotally attached to the panel face by the pivot pin *h*, and carries the three corresponding spring contact terminals 53a, 54a, and 55a, arranged and positioned to contact their respective terminal points 53, 54, and 55 when closed thereon under reaction of the attached spring 57, when otherwise unrestrained. The said series of contact terminals are opened by direct contact with the end of the timing rack 51 when moved in that direction by the connected operating motor 46. Positioned along the opposite side of the frame panel 49, and adjacent the opposite end of the timing rack 51, is a pair of adjustable contact terminals 58, and 58a mounted on an insulating block 59, and with the contact points normally open. The insulating block 59 is fixedly attached to the end of a toothed rack 60 which is slidably mounted across the inside face of the front frame panel 61. The toothed rack 60 meshes with and is adjusted by the connecting pinion gear 62 mounted on the operating stud shaft 63. The shaft 63 is rotatably mounted through the central section of the front frame panel 61, and is provided with a suitable handle 64 attached to the outer end thereof, for adjusting the position of the timing contact terminals 58 and 58a relative to the end of the closing rack 51, designed to close these terminals at predetermined intervals. Other types of motors and terminal operating elements, may also be adapted, if desired.

Directly above the timing unit B, is mounted the interlocking relay C and the transfer relay D, arranged one over the other and fixedly attached to the back frame panel 41. Both the relays C and D are shown as of the double, dual terminal type, and comprise an energizing coil *k*, magnetic core *m*, and movable armature plate *n*. The control relay D is provided with double, separated circuit contact terminals, 65 and 66 on one side thereof, and like double, separated circuit contact terminals 67 and 68 along the opposite side of the relay. A pair of double spring terminal contacts 69 and 70 are mounted on the relay armature plate *n*, positioned with their respective contact points between the pairs of double, separated, terminals 65-66, and 67-68. The contacts 69 and 70 are operative with the relay armature plate *n*, and their contact with the respective terminals depends upon the energizing or deenergizing of the relay coil *k*.

The interlocking relay C, is of a like structure, and is provided also with two pairs of separated contact terminals 71 and 72, also 73 and 74, and the corresponding double spring terminal contacts 75 and 76 positioned therebetween as in the former case.

To more clearly define the various separated electric circuits through the adapter, and the connected detector and signal timing units, and the sequence of operation, a simplified conventional timer unit is here illustrated, shown in the Figs. 8 and 9 of the drawings. The timer unit as here shown, comprises a support frame 11, and is provided with an electric power unit formed of dual coils 18 and 18a mounted therein in horizontal alignment, positioned with their respective magnetic poles slightly separated. An armature disc 80 is rotatably mounted in the frame 11 by the shaft 81, positioned with the disc edge between the power coil pole ends, and will rotate whenever the electric circuit is closed through the motor coils. Any other suitable electric motor unit could be substituted therefor, if desired. The rotation of the disc 80 and supporting shaft 81, also rotates the back gears 82, 83, and 84, with connecting gears, together with a connected operating cam 85. The operating cam 85 is formed of adjustable circular segments of different radii, connected together so as to form stepped circumferences *r*, *s*, *t* and *u* therearound providing different elevations for the contacting operating arm 86 engaged therewith as said cam is slowly rotated by the connected motor 18. The different stepped cam surfaces *r*, *s*, *t* and *u* control the operating arm positions for actuating the main street green (actuated street red), main street amber, main street red (actuated street green), and the actuated street amber signals, respectively. The outer end of the operating arm 86 is provided with a terminal contact cross pin *w*. A series of corresponding movable circuit contact terminals 87, 88, 89, and 90 are mounted on the insulating block 79 fixedly attached to the frame 11, said terminals contacting separated insulated terminal plates 91 and 92 also mounted on the insulating block 79. Each terminal is formed with a recessed section *x* therein, at a predetermined position for engaging the operating arm crosspin *w*, when the arm 86 has reached its corresponding elevation, thus allowing the respective terminals to close on the contact plates therebeneath, for closing the electric circuit corresponding to the different stepped sections of the disc 85. The duration of the different circuit closing periods are

determined by the adjustment of the segment sections *r*, *s*, *t*, and *u*. As the operating cam 85 continues to rotate, the contacting operating arm 86, after completing the actuated street amber period, is then returned to its initial position, by any suitable mechanical means, preferably either cam, or spring means, or both combined, but which has not been herein illustrated.

When the adapter unit is properly wired for their various electric circuits, the circuits of the adapter, as well as those of both the connected detector and signal timing units, function in unison, or in some predetermined sequence as is apparent from the wiring diagram shown in the Fig. 11 of the drawings, and the following disclosure. Whenever any automobile passes over the detector unit G installed beneath the actuated street surface, an induced electric current will be generated within the detector element coil 10 and is transmitted directly to the sensitive relay 1 through the connecting circuit wires 7 and 8, causing the rotor 5 and connected contact arm 11 to turn slightly for engaging said arm 11 with the fixed terminal 12. The relay may also be energized by an electric switch circuit. The contact terminals 11 and 12 are connected in the main electric circuit leading to the induction motor 2, by the circuit wires 13 and 14, thus energizing said motor, and cause rotation of its connected toggle arm 20 and attached side cam 24 in clockwise direction, momentarily opening the contact terminals 26 and 27, also opening the terminals 34 and 34a and closing the terminals 33 and 33a which are locked in that position by the connected latch arm 40 and lock arm 41 engaging therewith, and at the same time the reset arm 21 is rotated in direction for separating the relay contact terminals 11 and 12, disconnecting the circuit leading to motor 2. The arm 20 and attached cam 24 are then returned to their original position by the connected spring 32, again allowing the terminals 26 and 27 to close. The contact terminals 33 and 33a, as well as terminals 26 and 27, being closed, will likewise close the electric circuit leading to the signal timer unit power motor 78, through the connecting circuit wires 79, 79a, 79b, starting the timer motor and connected timing disc 85. This constitutes the full initial impulse through the adapter unit. Any subsequent impulse may also be registered during the call registering period indicated in the diagram shown in Fig. 10.

Assuming that the intersecting street, or actuated street traffic signal K is operating with a red, or "stop" signal thereon, and the main street signal M is operating with a continuous green, or "go" signal thereon, the initial starting of the timer unit motor 78, and connected operating disc 85 which will rotate through the remaining portion of the main street green disc section *r*, through the main street amber section *s*, and as the main street red (actuated street green) section *t* starts contact with the operating arm 86 closing the corresponding timer circuit contact terminals 89 and 91, the time extension interlocking relay C will be energized from the actuated street green circuit through the connecting circuit wires 93 and 93a. The closing of the relay C will open the terminals 73 and 76 and connected circuit wires 94 and 94a, which will allow a short time extension from the call registering unit A to the actuated street green period of the timing unit, each time an impulse call is registered, by the momentary opening of the sensitive relay terminals 26 and 27, thus stopping

the timer motor 78 for a short time each such impulse is registered. The duration of this time extension is regulated by adjusting the position of the contact terminals 26 and 27 relative to the adjacent operating side cam 24, by means of the adjusting screw 30 connected therewith. The relay C may be omitted where time extension is not material to the signals.

Likewise, as the signal timer continues to rotate the operating disc 85 to the actuated street section *u*, thus contacting the timer terminals 89 and 90 in their respective corresponding circuits and street signal lights, the call cancelling relay E is energized through the connecting circuit wires 95 and 95a, closing the relay armature plate *d* and automatically tripping the lock bar 41, thus canceling any registered call. The relay E will remain energized during the passing of the actuated street amber disc section *u*, and holds the connected contact terminals 42 and 43 closed to keep the timer motor in operation during this amber period if the amber should incidentally overlap the green section period. When the signal timer has reached the end of the amber section *u* of the operating disc 85, if no new calls have been registered, will return to the main street green section *r* as illustrated in Fig. 8 of the drawings, (by any suitable means employed for that purpose), again closing the corresponding timer contact terminals 87 and 91, thus energizing the adapter timer motor coil *aa* of the motor 46, through the connecting circuit wires 96, 96a, 96b, 96c, 96d and 96e operating through the closed terminals 65 and 69 of relay D. The energizing of the motor coil *aa* will cause rotation of the reversible motor 46 and connected pinion gear 50, in a direction for releasing and closing the circuit terminals 53, 54, and 55, and for contacting and closing the circuit contact terminals 58 and 58a, by operation of the connected actuated rack slide 51. The closing of the terminals 58, and 58a will energize the transfer relay D through the connecting circuit wires 96, 97, and 97a, and then hold the relay so energized through the closed contact terminals 69 and 66 and connecting circuit wires, as the relay armature closes thereon. As the relay D is closed, the electric circuit is transferred from the motor coil *aa* of the reversible motor 46, to the opposite motor coil *bb*, by the opening of the relay contact terminals 69 and 65 and the closing of the opposite terminals 68 and 70, thus shunting the electric current through the connecting circuit wires 98 and 98a and closed terminals 54 and 54a, to the motor coil *bb*, thus reversing the motor rotation. The reversed motor rotation likewise reverses the movement of the slide 51, which will continue in the opposite direction until the slide end reengages the terminal block 56 and again re-opens the contact terminals 53, 54, and 55, and likewise opening the circuit leading to the motor coil *bb*, stopping the motor 46. The opening of the adapter timer terminals 55 and 55a, likewise breaks the circuit to the signal timer motor 78 and stops rotation of the connected operating disc 85 while still on the main street green section *r*, preferably just prior to change to the adjacent amber section *s*. The stopping of the disc 85 in this position, will retain the signal timer terminals 87 and 91 closed and thus continue the main street green signal indefinitely, until the signal timer motor 78 is again restarted by a subsequent impulse call from the registering unit A, and repeating the operation. If a single phase motor is used in place of the reversible mo-

tor 46, with suitable terminal operating elements, as indicated in Fig. 11, then the transfer relay D may also be omitted.

Any suitable type of timer unit that will function for the different street signal light circuits, may be used in place of the timer herein illustrated. Likewise various different types of detector units may be substituted for the unit G herein shown.

It is apparent that my device is subject to various modifications in both design and unit arrangement, without departing from the spirit of my invention, and I claim not only the structure herein illustrated, but any modification thereof that is substantially a substitution of the parts and sections herein shown.

Having fully described my street signal adapter, what I claim as my invention and desire to secure by Letters Patent is:

- 20 1. An electric street signal adapter designed for converting alternating street signal units into special traffic actuated signal units, and used in combination with an electric detector and a motor operated alternating street signal timer, comprising a traffic electric impulse registering unit, circuit means for electrically connecting the registering unit with the detector in a manner for receiving electric impulses therefrom, circuit means for electrically connecting said registering unit with said alternating street signal timing unit motor in a manner for starting the timing unit when traffic impulses are registered, an electric circuit timing unit, circuit means for electrically connecting said circuit timing unit with the signal timing unit motor in a manner for stopping the signal timing unit at pre-determined periods, a time extension unit, circuit means for electrically connecting said time extension unit within an electric circuit leading through the call registering unit and to the signal timing unit motor, in a manner for momentarily stopping said motor for various traffic impulses registered, a traffic impulse call cancelling relay, circuit means for electrically connecting said relay in an electric circuit leading through and controlled by the signal timing unit, and mechanical means connected to and actuated by said call cancelling relay for releasing the registering unit mechanism at predetermined periods.
- 25 2. An electric signal adapter for converting a street alternating signal device into a special traffic actuated signal device, and used in combination with an electric impulse detector unit and a motor operated alternating street signal timing unit, comprising a traffic electric impulse registering unit including a sensitive relay instrument for actuating same, circuit means for electrically connecting said relay with the detector in a manner for receiving electric impulses therefrom, circuit means for electrically connecting said impulse registering unit within an electric circuit leading to the street signal timing unit motor, in a manner for starting the same when various detector electric impulses are received by the registering unit, an electric time extension relay, circuit means for electrically connecting said time extension relay within an electric circuit leading through the call registering unit and to the street signal timer motor, in a manner for momentarily stopping said signal timer motor and connected timing mechanism for various traffic signal impulses registered, a motor driven circuit timing unit, circuit means for electrically connecting said circuit timing unit within the signal timing unit circuit for regulating
- 30
- 35
- 40
- 45
- 50
- 55
- 60

- 75

and stopping said signal timing motor and mechanism at predetermined periods, a call cancelling relay, circuit means for electrically connecting said relay in an electric circuit leading through and controlled by the signal timing unit, and mechanical means mounted on and actuated by said call cancelling relay for releasing the registering unit mechanism at pre-determined periods.

3. An electric signal adapter to be used with an electric impulse traffic detector and a motor operated alternating street signal timing unit, comprising a call registering unit formed of a sensitive galvanometer relay, a small induction motor, series of circuit contact terminals mounted on the relay frame, mechanical operating units mounted between said relay and induction motor, connected to and actuated by said motor, circuit means for electrically connecting the galvanometer relay operatively with the detector unit, circuit means for electrically connecting the galvanometer relay operating contact terminals with the induction motor energizing coil in a manner for starting rotation thereof, circuit means for electrically connecting said registering unit actuated circuit contact terminals in various electric circuits leading to the street signal timer unit motor in a manner for stopping same for predetermined periods, a time extension relay, circuit means for electrically connecting said time extension relay within an electric circuit leading through the call registering unit operating terminals and to the street signal timing unit motor in a manner for momentarily stopping said signal timing motor at pre-determined intervals of the registering unit actuations, a circuit timing unit comprising an induction motor with various series of circuit contact terminals mounted thereon, mechanical operating means mounted on said motor and actuated thereby for automatically opening and closing said attached terminals in pre-determined order, circuit means for electrically connecting the various series of contact terminals within separated electric circuits leading to the signal timing unit, for controlling and stopping same at pre-determined periods of its rotation, a call cancelling relay, circuit means for electrically connecting said call cancelling relay in an electric circuit leading through the signal timing unit, and mechanical operating means connected to and actuated by said call cancelling relay for tripping the registering unit mechanism during pre-determined periods of the instrument operations.

4. An electric signal adapter to be used with an electric impulse traffic detector and a motor operated electric street signal timing unit, com-

prising a suitable supporting frame, an electric impulse registering unit, formed of a sensitive galvanometer relay instrument and an induction motor fixedly mounted on said frame, positioned 5 opposite each other, various series of circuit contact terminals mounted on said frame along opposite sides of said motor, mechanical operating means mounted adjacent said motor, connected thereto and actuated thereby, for opening and 10 closing different series of circuit terminals mounted within said registering unit in pre-determined sequence, circuit means for electrically connecting the relay energizing coil with the detector unit, circuit means for electrically connecting said relay contacting terminals in an 15 electric circuit leading through the induction motor energizing coil, circuit means for electrically connecting one series of circuit contact terminals in an electric circuit leading through the street signal timing unit motor energizing coil, in a manner for starting said signal timing motor and connected signal timing mechanism when a traffic impulse from the detector is transmitted to the registering unit, a time extension relay, circuit means for electrically connecting said extension relay energizing coil in an electric circuit leading through the circuit contact terminals of the street signal timing unit, in a manner for 20 momentarily stopping said signal timer motor for various traffic impulses received by the registering unit, a call cancelling relay, circuit means for electrically connecting said cancelling relay energizing coil in an electric circuit leading through 25 and controlled by the signal timing unit, mechanical operating means connected to and actuated by the call cancelling relay for tripping the registering unit mechanism during pre-determined periods of its operation, an electric circuit 30 timing unit formed of a reversible induction motor with various series of circuit contact terminals mounted thereon, mechanical terminal operating means mounted thereon, connected to and actuated by said motor for automatically 35 closing and re-opening the various connected series of circuit contact terminals in pre-determined order, circuit means for electrically connecting said motor operating coils and the various series of circuit contact terminals in separated 40 electric circuits leading to the timing unit, in a manner for automatically controlling said motor circuits and actuating the different series of contact terminals for stopping the connected street signal timing motor and connected mechanism 45 at a pre-determined period of its operation.

MASON V. GREEN.
